PAPER ARTICLE

Harold W. Martin, Malverne, N. Y., assignor to
American Seal-Kap Corporation, Long Island
City, N. Y., a corporation of Delaware

Application August 18, 1933, Serial No. 685,708

3 Claims. (Cl. 65—53)

This invention relates to paper articles in the nature of shallow receptacles, particularly suitable for use as coasters for supporting tumblers or other glasses out of contact with a table top or other supporting surface on which such articles are placed, or for use as ash trays or the like. The article, therefore, is made in the form of a flat shallow circular tray having an upwardly extended inverted U-shaped rim and preferably 10 provided with spaced depressed outside base portions by which it may be supported on a table or other surface.

For a more complete understanding of this invention, reference may be had to the accompanying drawing in which

Figures 1 and 2 are top and inverted plans, respectively, of an article constructed in accordance with this invention.

Figure 3 is a detail section to a larger scale 20 on line 3—3 of Figure 1.

Figure 4 is a section similar to a portion of Figure 3, but showing a modification.

Referring to the drawing, the article comprises a lower disk 1 of paper which has preferably been 25 treated with a waterproofing agent such as wax and a fire-proofing agent and has also been subjected to a moisture treatment which facilitates the molding operation. Advantageously this disk may first be subjected to a moisture and fire- 30 proofing treatment and then immersed in melted paraffin wax with preferably a small quantity of hardening wax such as carnauba or Montan, the wax being at such a temperature as to vaporize a portion of the water absorbed in the initial wet 35 treating so that on subsequent cooling, condensation of moisture acts to draw the wax into the pores of the paper. Sufficient water is retained, however, to condition the paper for subsequent molding operations.

The disk so treated is then subjected to forming operations between suitable dies to produce 40 a marginal U-shaped rim 2 thereon surrounding a central substantially flat depressed portion. Preferably this rim is formed with spaced radial 45 stiffening corrugations 3 over its upper edge. These corrugations not only facilitate the forming operation but also stiffen the margin so that it is more resistant to deformation and also produce an ornamental effect. The outer down- 50 turned edge portion of this rim, as at 6, is preferably pressed together so that it presents on its outer face a smooth curved contour. This pressure also acts to compact the paper material, which must be gathered together somewhat to 55 reduce it to the smaller diameter of its finished

condition over that of the blank from which it was made, so that it tends to retain its molded condition and is resistant to flaring out even when subjected to moisture. Preferably also the depressed portion of the disk within this margin 60 is formed with concentric downwardly extending corrugations or ribs, as at 4 and 5, to provide spaced supporting areas to contact with a table or other supporting surface on which the article may be placed, or, as shown in Figure 4 the rim 65 thus may be extended below the depressed or base portion of the disk. These ribs 4 and 5, or the downwardly extending rib 6 shown in Figure 4, with which may be used one or more depressed ribs on the base if desired, serve to define air 70 pockets beneath the article which act to protect the support on which the article is placed from the heat of burning material thereon when the article is being used as an ash tray.

On the central depressed portion of the disk 75 within the rim 2 is preferably positioned a second or liner disk 7 which may be of similar material to the other disk, but may, if desired, be of a more absorbent material so as to absorb condensation running down the outside of a glass or tumbler which may be placed thereon and thus prevent it from being spilled over onto the table or other supporting surface. This disk 7 is of sufficiently smaller diameter than the disk 1 so that its outer margin is in frictional engagement with 80 the inner upstanding wall of the rim 2 so that no fastening means for securing the two disks together is required. The article thus produced is in the form of a shallow receptacle having a rounded upstanding marginal rim which presents 85 a pleasing appearance and has sufficient rigidity to maintain its shape with ordinary usage. No cut edge of the disk appears since this is presented downwardly in the down-turned portion 6 at the outer edge of the rim. The corrugations across 90 the upper face of the rim also define depressed portions between them which tend to retain in position a cigarette or cigar placed thereon when this article is used as an ash tray.

In order that the liner disk 7 may be absorbent and at the same time be fire resistant, it may be treated with a soluble fire-proofing or resisting agent such as an ammonium salt, for example, ammonium sulphate, and an agent such as alcohol 105 which tends to soften and "fluff up" paper stock. The outer disk or shell 1 which should be relatively stiff and strong and non-absorbent may well be fireproofed by an ultimately insoluble agent such as sodium silicate which may be added to 110

the water with which the blanks are treated before they are subjected to the hot wax bath.

From the foregoing description of an embodiment of this invention, it should be evident to those skilled in the art that various other changes and modifications might be made without departing from the spirit or scope of this invention as defined by the appended claims.

I claim:

10. 1. A coaster comprising a disk of fibrous sheet material containing a waterproofing agent and having its margin pressed upwardly into inverted U-shape to form an upstanding rim, and a reinforcing disk seated on the central portion of said first mentioned disk and with its margin in frictional engagement with the inner upstanding wall of said rim, said first mentioned disk having concentric annular downwardly projecting ribs for engagement with a supporting surface and said reinforcing disk presenting a flat upper face over its entire area, said coaster being treated with fire-resistant material to adapt it to be used as an ash tray.
15. 2. A coaster comprising a paper disk having its margin pressed upwardly into inverted U-shape to

form a marginal upstanding rim surrounding a central substantially flat depressed portion, said rim having upwardly projecting radially extending reinforcing corrugations on its upper surface forming spacing ridges to receive a cigarette or cigar therebetween, and said coaster being treated with a fire-resistant agent whereby said coaster may be used as an ash tray.

3. A coaster comprising a fire-resistant paper disk having its margin pressed upwardly into inverted U-shape to form a marginal upstanding rim surrounding a central substantially flat depressed portion, said rim having upwardly projecting radially extending reinforcing corrugations on its upper surface, the material in the outer down-turned edge of said rim being pressed together into a substantially smooth continuous surface, and a fire-resistant reinforcing disk presenting a flat upper face frictionally engaged at its margin with the inner face of said rim, said first mentioned disk having concentric downwardly projecting ribs for engagement with a supporting surface, the fire-resistant quality of said coaster adapting it for use as an ash tray.
